CLAIM

The ornamental design for a display screen or portion thereof with animated graphical user interface, as shown and described.

DESCRIPTION

FIG. 1 is a front view of a display screen or portion thereof with animated graphical user interface showing the claimed design;

FIG. 2 is a front view of a second image thereof; and, FIG. 3 is a front view of a third image thereof.

The peripheral dashed broken lines depict a display screen or portion thereof, and form no part of the claimed design. The interior broken line ovals define the bounds of the claimed design and form no part thereof. All other broken lines show portions of the graphical user interface and form no part of the claimed design.

The appearance of the graphical user interface transitions between the images shown in FIGS. 1-3. The process or period in which one image transitions to another forms no part of the claimed design.

Four score and seven years ago our fathers
brought forth on this continent, a new nation,
conceived in liberty, and dedicated to
the proposition, that all men are
created equal.

Now we are engaged in a great civil war,
testing whether that nation, or any other
nation so conceived and so dedicated,
can long endure. We have met on a
great battlefield of that war. We have
come to dedicate a portion of that
field, as final resting place for
those who gave their lives that
that nation might live. It is altogether
fitting and proper that we should do
this.

But, in a larger sense, we can not
consecrate - we can not hallow - this
ground. The brave men, living and dead,
who struggled here, have consecrated
it, far above our poor power to add
or detract. The world will little note,
nor long remember what we say here;
but it can never forget what they did
here. It is for us the living, rather
to be dedicated here to the unfinished
work which they who
